*J. Beckwith,
Boring Timber.*

Patented Dec. 21, 1830.

Federal Burchard
Sawmill Patent

The Schedule referred to in the Sawmill Patent and making part of the same containing a description in the words of the said patent of Burchard himself of his improvement for boring timber.

To all to whom these Patents shall come

Be it known that I, Federal Burchard of the town of Saugerties in the County of Ulster and State of New York have invented a new and useful improvement for boring timber and that the following is a full and exact description of the construction and operation of the said machine as invented by me for working the auger. A exhibits on the accompanying sketch represents a shaft and wheel are inserted the auger ^{spud} B secured to and moving with the sliding frame C. D. represents the main frame consisting of two uprights ^{spuds} capped and mortised in the head B. and braced with grooves for C. to slide in. E. represents a crank and pinion wheel resting upon two upright posts marked G. mortised into the head of the frame and braced at N. to the main post which operating upon the rack H. attached to the sliding frame serve to raise or lower the auger, the same office may be performed by the line I attached to the top of the sliding ^{frame} and passing over sheaves wrought upon by a weight or wheel at K. L. represents a bevel gear and crank attached to the sliding frame the shaft of which fits in the slot M. cut out of one of the main uprights and acts upon the wheel P. attached to the shaft A. and turns the auger. O. holes in the bar piece and cap through which the auger passes timber above or beneath the machine. The machine is intended to be worked by hand or other power applied to the bevel gear shaft and to be used in boring all kinds of timber in any position. It will be useful in bridge & dock building. The dimensions of a machine capable of boring 25 inches deep are as follows. Bed frame B. 3 feet long 14 inches broad 3 by 4 inch timber. Uprights D. 4 1/4 long, cap 2 1/2 long timber 2 by 4 inch stuff. Sliding frame C. 2 1/2 long 20 inches

width. The horizontal wheel is 15 inches diameter. The front wheel is 24 inches diameter, shape of top, width 15 in. The pipe is 12.5 feet from extremity of iron head into which — angle is inserted, angle 180°.
